TABLE

Theodore W. Separa, 320 E. Breckenridge,
Ferndale, Mich. 48220

Filed Apr. 20, 1965, Ser. No. 84,881

Term of patent 3½ years

(Cl. D33—14)

FIG. 1 is a perspective view of a table embodying my design;

FIG. 2 is a front elevational view thereof;

FIG. 6 is a perspective view of the underside thereof.

I claim:

The ornamental design for a table, as shown.
